UNITED STATES PATENT OFFICE.

VERNE T. PRESSEY, OF WAVERLEY, MASSACHUSETTS.

AUTOMATIC SAFETY-GATE FOR RAILROADS.

1,237,091.

Specification of Letters Patent. Patented Aug. 14, 1917.

Application filed May 16, 1916. Serial No. 97,857.

To all whom it may concern:

Be it known that I, VERNE T. PRESSEY, a citizen of the United States, residing at Waverley, in the county of Middlesex and 5 State of Massachusetts, have invented certain new and useful Improvements in Automatic Safety-Gates for Railroads; and I do hereby declare the following to be a full, clear, and exact description of the invention, 10 such as will enable others skilled in the art to which it appertains to make and use the same.

This invention relates to new and useful improvements in automatic safety gates for 15 railroads and is particularly adapted for use in connection with subway and elevated railroads where the platform is raised above the track level.

Another object of the invention is to provide a gate which will prevent persons 20 standing on the platform from falling or being pushed off of the edge of the platform and onto the track.

Still another object of the invention is to 25 provide a gate which is automatically opened on the approach of the train and closed upon the withdrawal of the train.

Still another object of the invention is to provide a device which cannot be opened 30 until the train is in proper position before the platform for the boarding of the passengers and which will close before the train is in motion.

With these and other objects in view, the 35 invention consists in the novel combination and arrangement of parts which will be fully set forth in the following specification and accompanying drawings, in which:—

Figure 1 is an edge view of the gate showing the same as it would appear in use in connection with the platform and track.

Fig. 2 is a sectional view on line 2—2 of Fig. 1 showing the operating gears for the gate.

Fig. 3 is an enlarged detail view of the solenoids and contacts by which the movement of the gate is controlled, and

Fig. 4 illustrates the wiring diagram of the device.

Fig. 5 is a sectional view on line 5—5 of Fig. 1.

Referring to the drawings the numeral 1 designates the gate consisting of the vertical side bars 2 provided with the upper and 55 lower bars 3 which are connected intermediate their ends by the fillers 4. The

outer faces of the bars 2 are provided with rack teeth 5 which mesh with the gears 6 mounted on the shaft 7 which is journaled in the bracket 8. It will thus be seen that 60 upon rotation of the gears the gate will be raised or lowered. The platform is designated by the numeral 9 while the track is designated by the numeral 10 and consists of the usual ties 11 supporting the rails 12. 65 The ordinary third rail used in subways and elevated railway systems is designated by the numeral 13 and supported on the standards 14 beside the track and is arranged on the side opposite the platform 9. Supported 70 on the side of the track nearest the platform is a suitable longitudinally extending beam or bar 15 carrying the contacts 16 and 17 the use of which appear as the description proceeds. A suitable resistance unit 18 is 75 secured beneath one of the ties and one terminal thereof is connected by the wire 19 to the third rail 13 hereinbefore referred to.

Supported beneath the platform 9 is a suitable supporting platform 20 on which 80 the motor 21 is mounted and this motor is provided with the pinion 22 which meshes with one of the gears 6 so that upon rotation of the armature of the motor the gears 6 will be driven. It will thus be seen that 85 the gate 1 is controlled through the operation of the motor and thus the same may be moved to raised position. A suitable starting rheostat 23 is mounted on the supporting platform 20 beside the motor and is of 90 the automatic type and so arranged as to avoid overloading the motor before the same has attained the proper speed.

Supported on the under side of the platform 9 is the latch solenoid designated by 95 the numeral 24 and this solenoid 24 is adapted to attract the head 25 of the latch bar 26 which is slidably mounted in the bracket 27. A disk 28 is secured to the latch bar intermediate its end and a compression coil 100 spring 29 is interposed between one of the brackets 27 and the disk to normally tend to move the latch bar 26 outwardly to cause its forward end to engage the teeth on one of the bars 2 of the gate 1. It will be understood that if so desired a second electromagnet 24 may be positioned in such a way as to engage the teeth of the opposite bar 2 and thus prevent any possibility of the gate sagging at one end. A suitable bracket 30 110 is secured to the under side of the platform 9 intermediate the bracket 27 and the lower

end of the last named bracket is bent angularly as at 31 to form a pivotal support for the contact lever 32, the upper end of which is bifurcated to receive the pivot pin 33 which extends through the latch bar 26 and is so arranged that upon movement of the latch bar the lever 32 will be swung. A suitable plate of insulation designated by the numeral 33' is supported at the lower 5 end of the contact lever 32 and carries the contact plates 34 to which the conductor wire to be more fully hereinafter described is attached. A suitable spring arm 35 is supported on the sub-platform 36 positioned 10 beneath the platform 9 and carried on its upper end is the insulating plate 37 which supports the contact plate 38 having connected thereto a suitable conductor wire which will be more fully hereinafter 15 described.

Mounted in the rear of the latch solenoid 24 is the control solenoid 39 which is adapted to attract the head 40 of the sliding rod 41 which is slidably mounted in the bracket 42 and carries the pin 43 which will be more 20 fully hereinafter described. A suitable stop pin 44 is secured intermediate the ends of the bar 41 and forms an abutment for one end of the compression coil spring 45 the opposite 25 site end of which bears against one of the brackets 42. It will thus be seen that the spring will tend to hold the head 40 away from the electromagnet 39 as illustrated in Fig. 3. A depending bracket 46 is secured 30 to the under side of the platform 9 and the lower end thereof is bent as at 47 to form a pivotal support for the lever 48, the upper end of which is bifurcated to fit around the pin 43. It will thus be seen that when the 35 rod 41 is moved the lever will be swung on its pivot in the manner of the lever 32 hereinbefore referred to. One side of the lower end of the lever 48 carries a plate 49 formed of a suitable insulating material which in turn supports the contact plate 50 while the 40 opposite side of said arm carries the insulating plate 51 which in turn supports the contact plate 52. A suitable contact plate 53 is mounted on the insulating plate 54 carried on the upper end of the spring 55 and the plate 53 is adapted to be engaged by the plate 50 when the arm 48 is in the 45 position shown in the drawings. The spring 55 is mounted on the sub-platform 36 as is the spring 56 which supports at its upper end the contact plate 57 which in turn supports the contact plate 58 and it will thus be 50 seen that when the arm 48 springs in the position opposite that shown in Fig. 3 the plate 52 will engage the plate 58.

Passing now to the description of the wiring diagram reference will be had to Fig. 4 and it will be seen that when a train approaches the station a suitable contact shoe 55 not shown, which is carried by the train

bridges the contacts 16 and 17 thereby permitting the current to flow from the rail 13 into the wire 19 and thence through the resistance 18 and the wire 59 into the contact 17 thence through the shoe contact 16 and 70 into the wire 60 where it is carried upwardly to the magnet 39. The current then passes from the magnet through the wire 61 back to the track rail 12 forming the return circuit. The energization of the magnet 39 75 will cause the head 40 to be attracted thereby causing the lower end of the arm 48 to swing into such position as to bring the plates 52 and 58 into contact. This movement will cause the current passing from 80 the resistance 18 to enter the wire 62 and thence pass through the wire 63 carried by the movable arm 48 into the plate 52 and whence it will pass into the plate 58 and then into the wire 64 from which it enters 85 the solenoid 24. The current then returns through the wire 65 to the return wire 61 and back to the track rail 12. The energization of the magnet 24 will cause the head 90 25 to be attracted thereby swinging the lever 32 into such a position as to cause the plate 34 to engage the plate 38 and simultaneously withdraw the latch bar 26 from engagement with the teeth 5 of the rack bars supporting the gate. It will thus be seen 95 that the gate will be allowed to drop into open position and persons permitted to board the train. When it is desired to start the 100 shoe is raised to disengage the contacts 16 and 17 and it will be seen that this movement will deenergize the electromagnets 39 and 24 and permit the bar 41 of the magnet 39 to move outwardly under the influence of the spring 45 thereby swinging the arm 48 into such a position as to cause the contact plates 50 and 53 to engage thereby 105 allowing the current to flow from the resistance 18 through the wire 62 and wire 63 into the wire 66 from whence it passes into the wire 67 carried by the arm 32 and into 110 the contact plate 34. This contact plate remains in engagement with the contact plate 38 through the fact that the latch bar 26 bears against one of the vertical bars 2 and thus current continues through the plate 38 into the wire 67 and thence through the 115 automatic starting rheostat 68 into the motor 69 thereby setting the motor in operation. The current then passes through the wire 70 into the wire 61 and back to the rail 12. The motor will cause the gate to rise to the 120 position shown in Fig. 1 until the slot in one of the bars 2 has been reached at which time the latch bar 26 will enter said slot thereby permitting the lever 32 to swing 125 into such position as to cause the plates 34 and 38 to disengage and break the motor circuit.

While in the foregoing there has been shown and described the preferred embodiment

ment of this invention, it is to be understood that such changes may be made in the combination and arrangement of parts as will fall within the spirit and scope of the appended claims.

What is claimed is:—

1. A gate operating mechanism including a lifting motor, an electromagnet controlling the motor circuit, a latch actuated by said electromagnet and a second electromagnet for controlling the energization of the first mentioned electromagnet, the latch being adapted to engage the gate when in its raised position to hold the same in raised position.

10 2. A safety gate for electric railroads including a gate, a motor for moving the gate into closed position, said gate being automatically returned to open position, a latch for holding the gate in closed position, an electromagnet for operating the latch to move the same out of engagement with the gate, a control magnet controlling the passage of current through the latch magnet and the passage of current through the 25 motor circuit.

3. In a safety appliance for railways, a vertically slideable gate, a motor for moving the gate into closed position, said gate being adapted to move by gravity to open position, a latch for holding the gate in closed position, an electromagnet for releasing the latch, a contact arm actuated by the releasing of the latch for cutting in the motor circuit, a control magnet for controlling the 35 energization of the latch magnet and the completing of the motor circuit and means for enabling the power used for energizing the magnets and operating the motor to be taken from the feed wires of the railroad.

40 4. In a device of the class described, a vertically slideable gate, a motor for moving the gate upwardly and into close position, said gate moving by gravity to open position, a latch for engagement with the gate to hold 45 the same in raised position, an electromagnet for releasing said latch, an arm actuated upon the releasing of the latch, a motor controlled contact carried by the arm, a stationary resilient arm, a motor controlled

contact carried by the last named arm and 50 adapted to be engaged by the contact of the first named arm, a control magnet, an arm actuated by the control magnet, a contact carried by the arm, a relatively stationary contact adapted to be engaged by the contact on the arm, one of the contacts being adapted to complete the circuit through the latch magnet when the control magnet is energized the other contact being adapted to complete the circuit through the motor when 60 the control magnet is deenergized and means to control the energization and deenergization of the control magnet.

5. In combination with an electric railway, a safety appliance including a vertically movable gate, said gate being adapted to move into open position by gravity, an electric motor controlling the upward and closing movement of the gate, said gate being provided with a latch opening, a latch 70 for engaging the opening when the gate has moved through its uppermost position for supporting said gate in its downward movement, an electromagnet for releasing the latch, a motor controlled contact actuated 75 by the movement of the latch and adapted to be broken when the latch moves into the opening in the gate, a control magnet for controlling the energization of the latch magnet, contacts actuated by the control 80 magnet and arranged so that when said control magnet is energized the circuit will be completed through one of the contacts and the latch magnet, said contacts also being arranged so that when the control magnet is 85 deenergized and the latch out of the opening the circuit will be completed through the motor to cause the gate to move to closed position and means controlling the energization and deenergization of the control magnet. 90

In testimony whereof I affix my signature in presence of two witnesses.
